UNITED STATES PATENT OFFICE.

FREDERICK WILLIAM MANN, OF BERKELEY, AND MARVIN LEE CHAPPELL, OF EL SEGUNDO, CALIFORNIA, ASSIGNEES TO STANDARD OIL COMPANY, OF RICHMOND, CALIFORNIA, A CORPORATION OF CALIFORNIA.

APPARATUS FOR THE MANUFACTURE OF AROMATIC BODIES FROM PETROLEUM-OILS.

1,249,444.

Specification of Letters Patent. Patented Dec. 11, 1917.

Application filed May 3, 1917. Serial No. 166,131.

To all whom it may concern:

Be it known that we, FREDERICK WILLIAM MANN and MARVIN LEE CHAPPELL, citizens of the United States, residing the said 5 MANN at Berkeley, in the county of Alameda and State of California, and the said CHAPPELL at El Segundo, Los Angeles county, State of California, have invented certain new and useful Improvements in 10 Apparatus for the Manufacture of Aromatic Bodies from Petroleum-Oils, of which the following is a specification.

Our invention relates to an apparatus for the manufacture of aromatic bodies from 15 petroleum oils containing oils of the carbocyclic series, and is particularly applicable for the production of benzol, toluol, xylol and other aromatic bodies, by dehydrogenation under vacuum, as typified generally by that process disclosed in Patent No. 20 1214204, granted Jany. 30, 1917, upon our application for "Process for the production of aromatic bodies and gas from petroleum oils," to which said patent we herein expressly refer both for a confirmatory 25 understanding of the use of our present apparatus and for a disclosure of its distinctive novelty, to wit, its application of the heat; in this case the gases of combustion 30 being mixed with the injected oil and air.

Our invention comprises a converter containing the contact mass; means for supplying the oil to be treated, together with the necessary volume of air, to said converter; 35 additional means for producing an internal combustion in the converter from a hydrocarbon and air introduced into the converter in such a ratio and such quantities as to make a complete combustion and producing 40 thereby sufficient heat to bring about and to maintain the desired reaction-temperature; and means for maintaining in said converter, during treatment of the oil, a pressure below atmospheric.

45 The advantages of this apparatus due to its preferred construction as herein described as follows: First—a saving in fuel. Second—prolongation of the life of the vertical converter on account of being properly interiorly insulated by suitable lining. 50 Third—a more constant temperature maintenance throughout the section containing the contact mass, by which an increased

yield of the desired aromatic oil products is obtained. Fourth—a saving in labor. 55

In the accompanying drawing, to which reference is hereby made,

Figure 1 is a general view, more or less diagrammatic, of our apparatus, the vertical converter being in section. 60

Fig. 2 is a vertical sectional elevation of a slightly modified converter member of the apparatus.

1 is an oil storage tank which is filled by means of a pipe 2. From the storage tank 65 1 leads a pipe 3, controlled by a valve 4, to a preheater 5 which contains a steam coil 6 connected with a steam boiler, not shown, and controlled by valves 7 and 8.

From the preheater 5 leads a pipe 9 to 70 spray nozzle 10 with a pipe branch connection 11, controlled by a valve 12, which connects with a source of air supply, not shown. The flow of oil from pipe 9 is controlled by valve 13. 75

14 is a cylindrical iron or steel shell of the converter, said shell being lined at 15 with fire brick or kieselguhr brick, or both. The upper section of the converter is filled 80 with a suitable contact mass 16, which is of the nature described in our process patent hereinbefore referred to, namely a porous body impregnated with the lower oxid of a metal or metals, preferably the lower oxid of nickel. 85

17 is a brick arch which supports the contact mass. 18 is checkered brickwork which forms part of the internal combustion or heating chamber of the converter, by which is brought about a uniform heating and 90 maintaining of the desired temperature of reaction in the upper or contact section of the converter.

19 is a burner through which oil and air or a hydrocarbon gas and air are introduced 95 by means of branch pipes 20 and 21 respectively, which pipes are controlled by valves 22 and 23.

24 is a pyrometer which indicates the temperature in the section of the converter containing the contact mass 16. From the retort issues a pipe 25 connected to branch pipes 26 and 27 controlled by valves 28 and 29. Branch pipe 27 opens into the air. Branch pipe 26 runs to a receiver 30. From 105 receiver 30 runs a pipe 31 to a coiled con-

denser 32 contained in condenser box 33. From the condenser box 33 a pipe 34 runs into a receiver 35. From the top of receiver 35 leads a pipe 36 to the suction end of a compressor 37 which discharges into a pipe 38 and through a coiled pipe 39 which is contained in a condenser box 40.

From condenser box 40 leads a pipe 41 to the bottom and along the bottom of a tank 42, the pipe in the bottom of the tank being perforated. From the top of the tank 42 leads a pipe 43 controlled by a valve 44, to gas holder 45. From the top of gas holder 45 leads a pipe 46 to any place where it may be desired to burn the gas that collects in said holder 45.

The use or operation of this apparatus, in carrying out our process is as follows:— Petroleum oils or petroleum distillate coming from storage tank 1 flows through pipe 3 into preheater 5 where it is heated to a temperature ranging from 150° to 250° C., and then flows through pipe 9 into spray nozzle 10 and is regulated by means of valve 13. This flow may be effected either by gravitation or under pump pressure, and the oil may be introduced either in a liquid state into the converter, or in the form of a vapor spray or gas, and mixed with a certain regulated quantity of air, namely 500 to 800 cubic feet of air for each 15 to 20 gallons of oil introduced. The air is admitted through pipe 11 and regulated by means of valve 12.

The temperature inside the converter is maintained at from 600° to 750° centigrade, by means of burner 19 through which is introduced oil and air or a hydrocarbon gas and air by means of pipes 20 and 21 which connect with a source of oil and air or a hydrocarbon gas and air respectively. The flow of oil and air or a hydrocarbon gas and air is controlled by means of valves 22 and 23 so that there is brought about a complete combustion without using an excess of oxygen and according to formula:

or

At the same time a pressure of from one to four inches of mercury below atmospheric pressure, that is 734.6 to 658.4 millimeters of mercury absolute pressure is maintained in the converter. This pressure below the atmospheric is maintained by means of the suction pipe 36 of compressor 37. The catalytic mass 16 in the converter becomes coated with carbon after the oil has been passing through it for some time. It is necessary to clean the mass at the end of each run ranging from 40 to 90 minutes duration. This is accomplished by closing valves 13 and 23 in the branch pipes 9 and 20 where by the flow of petroleum oil and fuel oil to the converter is interrupted. Simultane-

ously the valve 28 of the branch pipe 27 is opened and the valve 29 of the branch pipe 26 is closed. The supply of air to the converter is increased through branch pipe 11 by means of valve 12. The air acts on the carbon coating of the catalytic mass according to the reactions

The temperature in the converter rises from 750° to 850° C., during the oxidation of the carbon. At the end of from 20 to 40 minutes, the catalytic mass is freed from its coating of carbon. The quantity of air is then reduced to a point between 500 and 800 cubic feet and petroleum oil, oil spray or oil vapor and fuel oil is again turned into the converter in like manner and proportion as when a new start is made.

The passage of petroleum oils or petroleum distillates through the catalytic material, as described, produces 20 to 35% of a permanent hydrocarbon gas, mixed with the products of combustion, carbon dioxide and nitrogen, and 50 to 75% of aromatic bodies which pass from the converter by branch pipe 26 into the tank 30 where a portion of said bodies are condensed. From the tank 30 the uncondensed aromatic bodies and the gas pass through the condensing coil 32 in tank 33 where more of said aromatic bodies are condensed and run into the receiver 35. The permanent gases retain a portion of the light aromatic oils which are removed from the receiver 35, by the compressor 37 and being condensed in tank 40 by condenser coil of pipe 39 are collected in the scrubber or receiver 42 which contains scrubbing oil and is kept under a pressure of from 50 to 80 pounds per square inch by means of compressor 37 and the excess discharge valve 44, from which the permanent gas enters the gas holder 45 through pipe 43.

The aromatic bodies thus produced are collected in the tank 30 and receivers 35 and 42 and are pumped into a storage tank. Finally they are treated and fractionated by well known methods.

Other well known methods may be used in connection with this converter for collecting the aromatic bodies thus formed and to bring about circulation of the gas vapors and oils through the apparatus and to maintain the pressure of from one to four inches mercury below atmospheric pressure, as for instance, exhausters.

In place of the construction of the vertical L-shaped converter shown in Fig. 1, we may construct the converter in the shape of a straight, vertical cylinder as shown in Fig. 2.

We claim:—

1. An apparatus for the described purpose comprising a converter; a contact mass

in said converter; means for supplying to the converter, the oil to be treated, together with the volume of air required for the contemplated reactions in the presence of the contact mass; additional means for introducing to and burning within the converter a fluid fuel for producing complete combustion and maintaining the required reaction temperature; and means for producing and maintaining in the converter, during the treatment of the oil, a pressure below atmospheric.

2. An apparatus for the described purpose comprising a converter; a contact mass in the converter; means for supplying to the converter the oil to be treated together with the volume of air required for the contemplated reactions in the presence of the contact mass; additional means for introducing to and burning within the converter a fluid fuel for producing complete combustion and maintaining the required reaction temperature; a vapor outlet condensing and collecting system from said converter; a compressor connected on its suction side with said system for producing and maintaining in the converter during the treatment of the oil, a pressure below atmospheric; and a gas sor connected on its suction side with said system for producing and maintaining in the converter, during the treatment of the oil, a pressure below atmospheric; and a gas

condensing and collecting system connected with the discharge side of said compressor. 30

3. An apparatus for the described purpose comprising a converter; a contact mass in the converter; means for supplying to the converter the oil to be treated together with the volume of air required for the contemplated reactions in the presence of the contact mass; additional means for introducing to and burning within the converter a fluid fuel for producing complete combustion and maintaining the required reaction temperature; a vapor outlet condensing and collecting system from said converter; a compressor connected on its suction side with said system for producing and maintaining in the converter during the treatment of the oil, a pressure below atmospheric; a gas condensing and collecting system connected with the discharge side of said compressor; and a controllable outlet from the converter to the outer air, disposed with relation to the contact mass therein on the side opposite to that exposed to the air supply means. 40 45 50

In testimony whereof we have signed our names to this specification.

FREDERICK WILLIAM MANN.
MARVIN LEE CHAPPELL.
